Del., a corporation of Delaware

Application November 26, 1945, Serial No. 630,758

13 Claims. (Cl. 18—30)

1

This invention relates to fluid operable circuits, and particularly, to fluid operable circuits employing pressure converters for intensifying the pressure in the circuit.

In circuits employing pressure converters or pressure intensifiers it is customary to employ valves for making the pressure converter or intensifier effective or ineffective. The pressures developed by a converter used as an intensifier are usually quite high and difficulty is often experienced in finding valves which will shift freely under the intensified pressures. To counteract the tendency of the valves to stick, it is necessary to manufacture them very heavy and to provide large operating means such as solenoids and large springs in order satisfactorily to shift the heavy valve member.

Accordingly, it is the primary object of the present invention to provide a method of and apparatus for operating a pressure converter or intensifier which eliminates the necessity for shifting valves under the intensified pressures.

It is another object to provide an improved method of and apparatus for making a pressure converter and intensifier effective at any predetermined time in the operating cycle of the circuit of which it is a part.

Still another object is to provide a press operating circuit employing a pressure converter or intensifier in which the shifting of valves under high pressure is substantially eliminated.

These and other objects and advantages will become more apparent upon reference to the accompanying drawings in which:

Figure 1 is a diagrammatic view illustrating a circuit employing a pressure converter;

Figure 2 is a vertical section through a typical converter and is indicated by the line 2—2 on Figure 3;

Figure 3 is a transverse vertical section through the converter and is indicated on the line 3—3 on Figure 2;

Figures 4, 5, 6 and 7 are transverse sections through the converter and are indicated respectively by lines 4—4, 5—5, 6—6 and 7—7 on Figure 2;

Figure 8 is a view of a press operating circuit according to this invention;

Figure 9 is another press operating circuit according to this invention;

Figure 10 is a diagram of an electrical circuit for controlling the press circuits of Figures 9 and 10;

Figure 11 is a view of a molding machine employing the principles of this invention; and

Figure 12 is a diagram of an electrical circuit for controlling the molding press circuit.

General arrangement

According to this invention there is a pump

which supplies fluid for actuating a motor. Connected between the motor and the pump is a pressure converter which may be made effective or ineffective. When the converter is ineffective the pump supplies fluid directly to the motor and when the converter is effective the pump supplies fluid thereto and the converter supplies fluid at increased pressures to the motor.

The converter or intensifier which it is contemplated using is shown and described in the co-pending applications Serial No. 594,413, filed May 18, 1945, and Serial No. 603,067, filed July 3, 1945, now abandoned, both in the name of Warren R. Tucker and assigned to the same assignee as the present application.

This converter or intensifier includes a valve member which is rotated by a motor and is effective only during the time that the motor and valve member are rotating. According to this invention the shift-over to intensifier operation is accomplished by energizing the motor which drives the intensifier valve member. When the motor is de-energized the intensifier becomes ineffective and is bypassed by suitable conduit means.

In order to synchronize the shift-over to intensifier operation the motor may be energized by pressure responsive means actuated in response to any predetermined stimuli in the circuit.

Referring to Figure 1, there is diagrammatically illustrated the action of the pressure converter which is employed in the various hydraulic circuits illustrated in the subsequent views.

In Figure 1 there is a pump at 10 which draws fluid from a reservoir 12 through a conduit 14 and discharges fluid under pressure into the conduit 16. The flow in the conduit 16 is divided in the branch conduits 16' and 16'' and enters the chambers 18 and 20 of the pressure converter 22 generally indicated at 22.

The pressure converter 22 comprises cylinder 24 which has a central cylinder within which is reciprocable the piston 26 and the reduced diameter end cylinders within which are reciprocable the pistons or rods 28 and 30. The rod 28 reciprocates in the chamber 18 while the rod 30 reciprocates in the chamber 32. The piston 26 divides the central cylinder into chambers 20 and 34.

As mentioned before, the chamber 18 is connected with the conduit 16 and the chamber 20 with the conduit 16'', while the chamber 34 is connected by conduit 36 with exhaust and the chamber 32 is connected by conduit 38 with the inlet of the fluid motor 40; the motor outlet being connected by conduit 46 with exhaust.

As shown in Figure 1, the pump is supplying fluid to the upper area of the piston 26 and the upper end of the rod 28 while the lower end of the piston 26 is connected with exhaust and the lower end of the rod 30 is connected with the

motor 40. Thus, the pressure delivered to the motor is augmented over the pressure delivered by the pump by the ratio of the said upper areas to the area at the lower end of the rod 30. By apportioning the sizes of the piston 26 and the rods 28 and 30, any desired intensification of pressure may be had.

By providing valve means operable alternately to connect the opposite ends of the pistons with the pump while connecting the other ends with the motor 40 and with exhaust, a continuous operating system may be had. By further providing a plurality of reciprocating pistons the supply of fluid to the motor 40 may be in continuous and overlapping increments so that perfectly uniform movement of the motor results.

Pressure and flow converter

The intensifier comprises a cylinder block 50 which has a plurality of axial bores 52 circumferentially spaced about a central bore 54. The bores 52 provide cylinders within which reciprocate the pistons 56 having the oppositely extending reduced piston portions 58 attached thereto. The portions 58 reciprocate in bored cylindrical plugs 60 which are inserted from opposite ends of the block 50 into somewhat enlarged end portions of the bores 52. The piston 56 and the rods 58 define the upper working areas indicated at A and B and the lower working areas indicated at C and D. The working areas are connected by radial passages with the central bore 54 of the block 50 at different levels.

Within the bore 54 is mounted a valve member indicated at 62 which is supported on the anti-friction bearings 64 which has an operating shaft 66 whereby the valve member may be rotated. The block 50 has an inlet port 68 (Figure 3) and the valve member 62 has a groove 70 at the level of the said inlet port. The groove 70 is communicated with the levels of the connections to the areas A and B by a pair of oppositely disposed notches 72 which extend somewhat less than 90° about the periphery of the said valve member. The levels of the connections to the areas C and D are communicated with the groove 70 by a pair of oppositely disposed notches 74 which are similar to the notches 72 but which are disposed at 90° therefrom.

The valve member comprises the groove 76 at the upper end thereof and the groove 78 at the lower end thereof which communicate by a bore 80 with an outlet port 82 in the block 50. The groove 76 communicates with the level of the connection with the area A by means of the oppositely disposed notches 84 which are disposed at 90° with the notches 72 so that alternate communication may be had with the area A. The groove 78 is similarly provided with the notches 86 which are disposed at 90° from the notches 84.

Arranged at the level of the connection with the area B are the oppositely disposed flats or notches 88 which are disposed at 90° from the notches 72 so that the said notches will alternately communicate with the area B. The notches 88 are connected by radial bores with the central passage 90 in the valve member which communicates directly with an exhaust conduit 92. At the level of the connection with the area C are similarly arranged notches 94 which communicate with the central passage 90 and which are disposed at 90° from the notches 88.

It will be apparent that the rotation of the valve member 62 is effective first to direct fluid

from the inlet 68 to the areas C and D while connecting area B to the exhaust 92 and the area A to the outlet 82 and thereafter to reverse the said connections; that is to connect A and B to the inlet pressure, C to exhaust and D to the discharge port. It will also be apparent that by providing a plurality of cylinders and pistons, the same will operate to receive and to discharge fluid in overlapping increments so that substantially continuous operation may be had.

By connecting the motor with the shaft 66 and selectively energizing the motor the intensifier may be made effective or ineffective as desired. When the intensifier is effective the efficiency of conversion thereof is high and the energy of the working fluid represented by the production of pressure and volume is substantially the same at the inlet and outlet ports of the converter.

It will be obvious that the drive motor for the valve member could be of any type convenient to employ, such as fluid operable, and need not necessarily be an electric motor as shown.

Circuit of Figure 8

25 In Figure 8 there is shown a ram 100 having advancing means 102 and retracting means 104 and reciprocable in a cylinder 106. The advancing and retracting means are connected with the service ports of a four-way valve 108 which receives fluid from a conduit 110 and which has an exhaust conduit 112. The conduit 110 connects with the discharge side of a pump 114 through a check valve 116 opening toward the said valve. The pump 114 draws fluid from a sump or reservoir through a conduit 118 and expels it at increased pressures to the conduit 110.

40 The valve 108 is continuously urged into position to connect the conduit 110 with the retracting means 104 by a spring 120 is adapted for being moved into position to connect the conduit 110 with the advancing means by the energization of a solenoid S1.

45 The circuit of Figure 8 also includes the intensifier 22 which has its inlet port 68 connected by a conduit 122 with the conduit 110 and its outlet port 82 connected with the advancing means of the ram 100. A motor 124 has its drive shaft connected with the shaft 66 of the intensifier valve member and is adapted for being energized by the closure of the switch 126.

50 In operation, the solenoid S1 may be energized to direct the pump discharge to the advancing means 102 in order rapidly to advance the ram 100. In response to a predetermined position of the ram, or in response to a predetermined pressure on the said advancing means, or by manual means the switch 126 may be closed to energize the motor 124 to drive the valve member of the intensifier 22. When this takes place the pump supplies fluid through conduit 122 to the intensifier and the intensifier supplies fluid from its outlet port 82 to the advancing means at increased pressure. During the high pressure operation of the ram 100, the check valve 116 blocks off the conduit 110 from high pressure flow. After the working stroke of the ram 100, the motor 124 may be de-energized and the solenoid S1 de-energized and the ram retracted to its Figure 8 position.

Circuit of Figure 9

55 In Figure 9 there is shown another press circuit in which the press ram 130 has its advancing means 132 connected by conduit 134 through a check valve 136 with one side of a reversible pump

138, and its retracting means 140 connected by conduits 142 with the other side of the said pump.

The pump is adapted for being placed in position to deliver into the conduit 134 by energization of a solenoid S2 and is continuously urged toward position to deliver to the conduit 142 by a spring 144. When the ram is fully retracted the linkage generally indicated at 146 is operable to shift the pump toward neutral in order to bring the ram to a halt.

The circuit of Figure 9 may also include a makeup check at 148, a surge valve at 150 and a main cylinder release and bypass valve at 152. Bypassing the check valve at 136 and having its inlet port 68 connected with the inlet side of the check valve and its outlet port 82 connected with the outlet of the check valve is the intensifier unit 22 having the valve member drive motor 124 adapted for being energized by the closure of the switch 126.

Also connected with the inlet of the check 136 is a conduit 154 which leads to the reservoir 156 and which includes the check valve 158 opening away from the said reservoir. The purpose of the valve 158 is to permit a supply of fluid to the pump 138 when said pump is delivering into the conduit 142.

In operation, the ram 130 may be started downwardly by energizing the solenoid S2 and shifting the pump 138 to deliver into the conduit 134. The ram will advance as rapidly as the pump withdraws fluid from the retracting means 140 and, upon striking the work, will advance as rapidly as the pump supplies fluid to the advancing means 132.

In response to a predetermined pressure on the said advancing means, or in response to a predetermined position of the said ram, or by manual means the switch 126 may be closed to energize the motor 124 to make the intensifier effective. When the intensifier is effective, the pump delivers fluid through the inlet port 68 and the intensifier delivers fluid at increased pressure through its outlet port 82 to the advancing means 132. During this time, the check valve 136 prevents the high pressure fluid from being bypassed back to the pump.

When the switch 126 is opened and the solenoid S2 is de-energized the spring 144 shifts the pump to deliver fluid to the retracting means 140. During the retracting movement of the ram 130 the fluid in the advancing means is expelled through the surge valve 150 and the pump draws fluid from the reservoir through the check valve 158. When the ram is fully retracted it engages the linkage 146 and shifts the pump from retraction stroke to neutral.

Electrical circuit of Figure 10

For automatically operating the hydraulic circuit of either Figure 8 or 9 there may be provided a circuit shown in Figure 10.

In Figure 10 there is connected between the power lines L1 and L2 the contactor coil A in series with the start switch 160. The start switch 160 is bypassed by the blades A1 of the contactor A which provide a holding circuit for the said contactor and which also energizes the solenoid S1 or S2 for placing the motor rams on their advancing strokes.

Also connected between the rams L1 and L2 is a contactor coil B in series with a switch 162 which, as previously set forth, may be operated in response to a predetermined position of the motor

ram or in response to a predetermined pressure on the advancing means thereof. The contactor B has a holding circuit comprising the normally open blades B1 which also energize the motor 124. In order to halt the advancing stroke of the ram and to commence the retraction stroke thereof, there is provided a switch 164 which is normally closed and which is operated in response to a predetermined position of the motor ram or in response to a predetermined pressure on the advancing means thereof. Opening of the switch 164 de-energizes the contactors A and B and, therefore, the solenoid S1 or S2 and the motor 124.

Circuit of Figure 11

In Figure 11 there is shown a molding press circuit utilizing this invention. In this view there is a clamping motor 200 adapted for clamping the mold halves 202 and 204 together so that molding material may be injected therein from the injection cylinder 206 by the injection plunger 208, the latter being operated by the fluid motor 210.

The motor 200 may comprise a double-acting ram 212 and a booster ram 214 arranged in a manner well-known in the art. The working area of the booster ram 214 and the retraction side of the ram 212 are connected to the service ports of a four-way valve 216. Pressure fluid is supplied to the inlet of the valve 216 from a pump 218 by conduit 220 which includes a check valve 222 opening toward the four-way valve. The four-way valve also includes an exhaust connection 224 and is continuously urged into position to connect the conduit 220 with the retraction side of the ram 212 by a spring 226 and is adapted for being moved into position to connect the conduit 220 with the working area of the booster ram by the energization of a solenoid S10.

During the rapid advance of the ram 212 by the booster ram 214, fluid is supplied to the advancing side thereof by a conduit 228 which includes a check valve 230, the inlet of which is connected with the reservoir and the outlet of which is connected with the said advancing side. During the retraction movement of the ram 212 the advancing side thereof is exhausted through the check valve 230 which is piloted to an open position by fluid conducted thereto through the pilot line 232 from the retraction side of the said ram.

In Figure 11 the booster 22 has its inlet port 68 connected with the conduit 220 between the pump 218 and the check 222 and its outlet port 82 connected with the conduit 228 between the check valve 230 and the advancing side of the ram 212.

The motor 124, connected with the intensifier valve member, is adapted for being energized by the closure of a pressure switch 232 which is operated into its closed position by pressure conducted through the pilot line 234 from the advancing side of the motor 210. In order to stabilize the operation of the switch 232 there is connected in series therewith the check valve 236 opening toward the said switch and the adjustable choke valve 238 in parallel with the said 70 check valve. By adjusting the valve 238 the opening of the switch 232 may be delayed for any predetermined length of time.

The injection plunger motor 210 has its opposite ends connected with the service ports of the four-way valve 240 which is supplied with fluid

from the conduit 242 and which exhausts fluid through a conduit 244. The conduit 242 may be connected with the discharge side of a pump 246 or may receive fluid from the pump 218 if desired.

The valve 240 is urged into position to connect the conduit 242 with the retracting side of the motor 210 by a spring 248 and is adapted for being shifted into position to connect the conduit 242 with the advancing side of the motor by the energization of the solenoid S12.

For automatically actuating the valves and for making the intensifier 22 effective there may be provided the electrical control circuit of Figure 12. In Figure 12 there is connected between the power lines L1 and L2 a contactor coil C having the blades C1 which provide a holding circuit for the said coil and which also energize a timer indicated at T. When the timer T is energized it closes the blades T1 thereof to energize the solenoid S10 and thereby rapidly to close the mold halves 202 and 204. A predetermined time after the blades T1 close, the blades T2 close and energize the solenoid S12 to bring about the advancing movement of the plunger 208. When the plunger 208 advances against the molding material and commences to build up pressure the switch 232 will be actuated to energize the motor 124 thereby to make the intensifier effective to deliver high pressure to the advancing side of the ram 212 to maintain the mold halves tightly clamped together.

The augmented thrust on the mold halves is sufficient to maintain them clamped together against the separating force of the injected molding material and thereby to prevent flash between the mold halves and to insure that the workpieces will be correctly shaped, correctly sized and that they will not require subsequent machining operations.

After a predetermined dwell of the plunger 208, the blades T2 open to de-energize the solenoid S12 to permit the retraction of the injection plunger. Due to the choke valve 238 the intensifier will remain in operation for a predetermined time after the retraction of the injection plunger to insure that the material in the mold will have a chance to be set or cured.

After the molding material has set for a sufficient length of time, the blades T1 open to de-energize the solenoid S10 to permit the retracting movement of the plunger 212. Thereafter, the blades T3 of the timer open and the circuit is ready for a new cycle to be commenced.

It will be apparent that the employment of this invention provides means for securely clamping mold halves together even when the projected area of the cavity thereof is large and the separating thrust due to the injected material is high. Also, by employing the intensifier as illustrated and interlocking it with the operation of the injection plunger, considerable power is saved and the clamping ram will be made of a relatively small size.

This invention also provides press operating circuits for a plurality of operating pressures in which the shift-over from one pressure stage to another is substantially instantaneous and eliminates the shifting of valves under high pressures.

While the motor for rotating the valve member has been shown as an electric motor to be actuated in response to the closing of an electric switch by pressure or by the position of the motor ram, it will be apparent that the motor for

the valve member could be a fluid operable motor which was energized by pressure fluid directed thereto by a valve actuated in response to a predetermined pressure or predetermined position of the motor ram.

It will be understood that this invention is susceptible to modification in order to adopt it to different usages and conditions and, accordingly, it is desired to comprehend such modifications within this invention as may fall within the scope of the appended claims.

I claim:

1. In a hydraulic circuit; a fluid source; a fluid pressure converter having an inlet port connected with said source and also having an outlet port and an exhaust port, piston means having opposed pairs of working areas thereon in said converter, rotary valve means in said converter movable to connect said inlet port with both of one pair of areas while connecting the others, one with exhaust and one with said outlet port; electric motor means for driving said valve member to make said converter effective; switch means selectively operable to energize or to de-energize said motor; and means including a check valve for bypassing the discharge of said pump around said converter when the latter is ineffective.

2. In a hydraulic circuit; a fluid source; a fluid pressure converter having an inlet connected with said source and also having an outlet and being operable to receive the discharge of said source and to discharge it from said outlet with the pressure-volume ratio thereof modified, said converter including a rotary valve member which must be driven during the time said converter is to be effective; motor means energizable to drive said valve member; means including a check valve for bypassing the discharge from said source around said converter when the latter is ineffective; and pressure responsive means for energizing said motor to make said converter effective.

3. In a hydraulic circuit; a fluid motor; a fluid source; converting means for receiving the discharge from said source at the first pressure-volume ratio and for discharging it to said motor at a second pressure-volume ratio, said converter including a valve member which must be driven to make said converter effective; motor means for driving said valve member; and means adapted for being operated by said fluid motor during the operation thereof for energizing said valve member driving motor means.

4. In a hydraulic circuit; a fluid motor; a reversible fluid source connected to drive said motor in both directions; fluid pressure converting means having its inlet connected with said source and its outlet connected with said motor and operable to receive fluid from said source and to discharge it to said motor with the pressure-volume ratio thereof modified; said converting means including a valve member which prevents fluid flow between the inlet and outlet of the converting means when stationary and makes the converting means effective when driven; motor means connected to drive said valve member; and means responsive to a predetermined pressure acting on said motor for energizing said drive motor.

5. In a hydraulic circuit; a fluid motor; a fluid source; a continuously operable pressure converter connected between said source and motor and comprising a plurality of pistons having double areas on the opposite ends thereof, and

a distribution valve operable to connect both areas on one end of said pistons with said source while connecting the areas at the other ends thereof one with exhaust and one with said motor and moveable to so connect said pistons in sequence; electric motor means energizable to drive said valve member; and pressure responsive means connected with said fluid motor and responsive to a predetermined pressure acting thereon for energizing said electric motor.

6. In a hydraulic circuit; a fluid motor; a fluid source of reversible delivery connected to supply said motor; a fluid pressure converter connected to receive the discharge of said pump and to discharge it at increased pressure and reduced volume to said motor and including a valve member rotatable to make said converter effective; motor means for driving said valve member; means responsive to a predetermined pressure acting on said fluid motor to energize said motor means; valve means bypassing the discharge from said source around said converter when the latter is ineffective; and other means bypassing said converter to permit a supply of make up fluid to said source.

7. In a hydraulic circuit; a reciprocable ram having advancing and retracting means; a fluid source of reversible delivery connected selectively to supply said advancing or said retracting means; a fluid pressure converter connected between said source and said advancing means and operable when effective to modify the pressure-volume ratio of fluid supplied to said advancing means; means responsive to a predetermined pressure acting on said advancing means for making said converter effective; a first check valve bypassing said converter to permit the supply of fluid to said advancing means directly from said source when the converter is ineffective; and a second check valve means bypassing said first check valve means for permitting a supply of fluid to said source when the latter is delivering to said retracting means.

8. In a hydraulic circuit; a fluid motor having a first and a second port; a reversible fluid source connected to deliver directly to said first port or to said second port through a check valve; a reservoir; means connecting said source to said reservoir to permit a supply of fluid from the latter to either side of the former; a fluid pressure converter bypassing said check valve and adapted for receiving the discharge of said source and for redischarging it at increased pressure and reduced volume and including a rotatable valve member which makes said converter effective when rotated; means responsive to a predetermined pressure at said second port for actuating said valve member; and means responsive to a supply of pressure from said source to said first port for connecting said second port with said reservoir.

9. In a hydraulic circuit; first and second fluid motors; pumping means connected by conduits with fluid to said motors; a check valve in the conduit to one of said motors opening toward the said motor; a fluid pressure converter bypassing said check valve and when ineffective offering no passage to fluid therethrough; and means responsive to a predetermined pressure active on the other of said motors for making said converter effective thereby to increase the pressure of the fluid supply to the said one of said motors.

10. In a hydraulic circuit; first and second

fluid operable motors; means for supplying actuating fluid to said motors; a fluid pressure converter operable to receive the supply delivered to one of said motors and to redischarge it to said motor at increased pressure; means responsive to a predetermined pressure acting on the other of said motors for making said converter effective; and a check valve bypassing said converter to permit a direct supply of fluid to said one motor when said converter is ineffective.

11. In a hydraulic circuit; first and second fluid operable motors; means for supplying actuating fluid to said motors; a fluid pressure converter operable to receive the supply delivered to one of said motors and to redischarge it to said motor at increased pressure; pressure responsive means connected with the other of said motors and operable in response to a predetermined pressure thereon to make said converter effective; and time delay means effective for a predetermined period following the reduction in pressure on said other motor below said predetermined pressure for maintaining said converter in effective operation.

12. In a hydraulic circuit; first and second fluid operable motors; means for supplying actuating fluid to said motors; a fluid pressure converter operable to receive the supply delivered to one of said motors and to redischarge it to said motor at increased pressure; pressure responsive means connected with the other of said motors and operable in response to a predetermined pressure thereon to make said converter effective, and means for maintaining said converter in effective operation for a predetermined period after the pressure acting on said other motor is reduced.

13. In a molding press; a clamping motor and an extrusion motor; means of supplying actuating fluid to said clamping motor and also to said extrusion motor; a fluid pressure converter serially connected with said clamping motor and selectively operable to receive the supply to said clamping motor and to redischarge it to said motor at augmented pressure; and means responsive to a predetermined pressure acting on said extrusion motor for making said converter effective and for maintaining said converter in effective operation for a predetermined period after the predetermined pressure is reduced.
